UNITED STATES PATENT OFFICE.

BENJAMIN N. BRODIO, OF NEW YORK, N. Y., ASSIGNOR TO THE SUPERHEATER COMPANY, OF NEW YORK, N. Y., A CORPORATION OF DELAWARE.

BOILER HAVING SUPERHEATER.

Application filed March 6, 1926. Serial No. 92,770.

This invention relates to a novel arrangement of boiler tubes and baffles for defining the gas passes in combination with an arrangement of superheater units.

The present tendency in steam engineering is towards the use of higher superheat. The required heat can be imparted to the steam, either by resorting to the expedient of increasing the length of the steam passage through the superheater or by placing the superheater units nearer to the furnace. The first of these expedients necessarily involves greater installation costs. To consider the second expedient in connection particularly with horizontal water tube boilers, at least two possibilities exist. A space may be made for the superheater within the tube bundle close to the furnace; but this will result in a higher and therefore more expensive boiler. A second possibility is to extend the superheater loops into the spaces between the water tubes so their lower ends approach the furnace. This will partially obstruct the passage for the gases and has therefore been hitherto thought objectionable.

The principal object of this invention is to provide a new and improved construction and arrangement of transverse baffles and superheater units in a boiler by means of which the desired high degree of superheat may be obtained without increasing the size of the superheater or materially impairing the efficiency of the boiler.

These results are obtained by placing the superheater units in the first gas pass of the boiler, between the boiler tubes, and arranging transverse baffles so that, notwithstanding the presence of the superheater units, a uniform velocity of the furnace gases will be secured in all passes of the boiler.

Other objects such as ready installation and removal of the superheater units, and simple and inexpensive manner of supporting the units will appear more fully from the following more detailed description and by reference to the accompanying drawings forming a part hereof, and wherein, Fig. 1 is a vertical section of a constructional example of a boiler embodying the principles of my invention taken lengthwise of the boiler tubes, Fig. 2 is a section substantially on line 2-2 of Fig. 1; Fig. 3 is a section on the line 3-3 of Fig. 2; and Figs. 4 and 5 are views similar to Figs. 2 and 3 of a different constructional example.

At 10 and 11 I have indicated the front and rear main headers respectively, connected by longitudinal tubes 12 which are inclined in the specific embodiments shown. At a certain distance below the set of tubes 12, I have illustrated a set of similar tubes 13, which connect auxiliary front and rear headers 14 and 15 respectively, such headers communicating with the respective main headers, as through tubes 16 and 17 respectively. An inclined baffle 18 is shown as extending above the set of tubes 13, from the front end of such set rearwardly and from the rear end of the inclined baffle 18 an upright baffle 19 extends upwardly across all the tubes of the upper set of tubes 12. This upright baffle may be inclined so that the passage 20 between the baffle 19 and the rear headers will be slightly contracted upwardly. The passage it will be noted is much larger than the passage usually provided for the first gas pass. At 21 I have indicated a drum of well-known type, the lower portion of which communicates with the front headers, as at 22, while pipes 23, 24 connect said drum with the upper section 11' of the rear headers. A second upright baffle 25 extends across the tubes 12 of the upper set, between the upright baffle 19 and the front header 10, and this baffle 25 is continued upwardly as at 26, to form, in conjunction with a baffle 19 and another baffle 27, respectively a downward passage 28 and an upward passage 29, the lower ends of these passages being connected by a passage 30, as the baffle 25 terminates short of the baffle 18. The upper ends of the passages 20 and 28 are connected by a passage 31 extending lengthwise above the tubes 12. It will be understood that the walls of the boiler setting or other structure are so arranged as to cause the hot gases from the combustion chamber to travel successively through the passages 20, 31, 28, 30, and 29 (in the order named) to the stack or other outlet.

The superheater elements extend within the passes 20 and 31, and are supported from above, in any suitable manner. In the embodiment illustrated, there are no superheater elements in the passages 28, 29, and 30. I have shown headers 32 for the saturated steam coming from the boiler and other headers 33 for the superheated steam to be delivered to the place of use or consumption. These headers are horizontal and transverse to the direction of the boiler tubes.

12, 13. In the particular embodiment shown, there are three groups of superheater elements, a front group 34, a middle group 35, and a rear group 36. The front header 32 and the rear header 33 are shown connected with the superheater elements of only one group (34 or 36 respectively) but each of the other superheater headers is shown connected with the superheater elements of two adjoining groups.

The superheater elements are of any suitable formation, preferably with return bends at their upper and lower ends, as shown. These elements extend downwardly (preferably vertically) across the greater portion of the passage 31, and then lengthwise of the passage 20, and preferably terminate above the set of tubes 13, so that the lower superheater bends are in the space between the sets 20 of tubes 12 and 13. While this is the preferred construction, I do not intend to restrict myself thereto. The superheater elements are preferably of gradually increasing length from rear to front, their lower bends 25 being arranged in an inclined line substantially parallel to the tubes 12, 13. The lower ends of the superheater elements are preferably above the set of boiler tubes 13.

In the form shown in Figs. 1 to 3 inclusive, 30 the spacing of the boiler tubes 12 transversely of the boiler is somewhat different from the usual spacing. As shown most clearly in Fig. 3 the tubes are arranged in vertically arranged groups each group consisting of 35 two staggered rows of tubes, and each group being spaced from the adjacent group a sufficient distance to provide a clearance space in which the straight vertically extending superheater units are located.

40 The invention is not limited however to the grouped spacing of the tubes shown in Figs. 1 to 3 inclusive but is equally applicable to a boiler in which the usual spacing of the boiler tubes is employed. In the latter case, 45 as shown in Fig. 5 the superheater units 35^a are sinuously curved to be between the tubes 12^a.

In each case the tubes may be inserted by 50 springing the headers 11, 11' towards the sides of the boiler, there being a sufficient space between the side face of the outermost headers and the inner faces of the side walls of the boiler to permit the headers to be moved sideways enough to allow the superheater units or elements to be passed between 55 adjacent headers and inserted between the boiler tubes.

The supporting of the superheater elements is remarkably simple, and as they are freely 60 suspended, as it were, the strains to which they are subjected by their own weight and by temperature changes, are reduced to a minimum. Furthermore, about two-thirds of the space across which the boiler tubes 12 65 extend, is utilized for the first gas pass in

which the superheater elements are located. With this arrangement of such elements, I secure not only a better superheating effect but also a more efficient heating of the boiler tubes.

The various parts are preferably so proportioned as to secure a uniform velocity of the combustion gases in the upward passage 20 and in the downward passage 28 (as well as in the upward passage 29). For this purpose, the effective or clear cross sectional area of the passage 20 (that is the total area of the passage, minus the space occupied by the water tubes 12 and by the superheater elements) is made equivalent to the effective or clear cross sectional area of the passage 28 (and of the passage 29). By using the term "equivalent," I intend to convey the fact that these cross sectional areas are not exactly equal, but the cross sectional area of the passage 28 (and of the passage 29) is reduced, relatively to that of the passage 20, in the same proportion as the combustion gases are reduced in volume owing to the lowering of their temperature.

While the superheater elements have been shown vertical or upright, and the water tubes inclined, with their headers 10, 11, 14, 15 upright, I desire it to be understood that the structure illustrated would be operative 95 in other positions as well.

Various modifications may be made without departing from the nature of my invention as set forth in the appended claims.

I claim:

1. A boiler of the type wherein a plurality of rows of water tubes are arranged to extend substantially horizontally over the boiler furnace, a plurality of baffles extend transversely across said tubes to provide a plurality of gas passes and a plurality of superheater elements are located in the gas pass nearest to the furnace, characterized by the provision of a plurality of superheater headers supported at the top of the boiler from which said superheater elements are freely suspended, said elements extending vertically into said nearest gas pass in the spaces between adjacent rows of said tubes, and said baffles being unequally spaced longitudinally of said tubes to compensate for the presence of said elements and so that the effective cross sectional areas of the gas passes formed between said baffles are equivalent.

2. A boiler of the type wherein a plurality of rows of water tubes are arranged to extend substantially horizontally over the boiler furnace, a plurality of baffles extend transversely across said tubes to provide a plurality of gas passes and a plurality of superheater elements are located in the gas pass nearest to the furnace, characterized by said water tubes being similarly arranged in closely spaced staggered relationship in pairs of rows, each of said pairs of rows being spaced

- transversely from the immediately adjacent pairs a sufficient distance to provide clearance spaces and being connected at their ends to common vertically extending steam headers, 5 a plurality of superheater headers extending transversely across said boiler at the top thereof and said superheater elements being freely suspended from said superheater headers and extending vertically into said 10 clearance spaces, there being sufficient clearance space between said steam headers and the sides of the boiler to permit said steam headers to be moved sideways for the removal of said superheater elements by movement 15 thereof longitudinally of said water tubes.
3. A boiler as set forth in claim 1 in which the baffles are so located longitudinally of the water tubes that a major portion of the length of each of said tubes is located in the gas pass 20 nearest to the furnace.
4. A boiler of the type wherein a plurality of rows of water tubes are arranged to extend substantially horizontally over the boiler furnace in a plurality of banks located 25 at different distances from said furnace, a plurality of baffles extend transversely across said tubes to provide a plurality of gas passes and a plurality of superheater elements are located in the gas pass nearest to 30 the furnace, characterized by the provision of a plurality of superheater headers supported at the top of the boiler and extending transversely thereof, said superheater elements being suspended from said headers and 35 extending vertically between said water tubes, the lower ends of said superheater elements terminating immediately above the bank of water tubes nearest to the furnace, and said baffles being unequally spaced longitudinally of said tubes to compensate for the 40 presence of said elements and so that the effective cross sectional areas of the gas passes formed between said baffles are equivalent.
5. A boiler of the type wherein a plurality of rows of water tubes are arranged to extend substantially horizontally over the boiler furnace, a plurality of baffles extend transversely across said tubes to provide a plurality of gas passes and a plurality of superheater elements are located in the gas pass 45 nearest to the furnace, characterized by the provision of a plurality of superheater headers supported at the top of the boiler, said superheater elements being suspended from said headers and extending vertically into 50 the spaces between adjacent rows of tubes and said baffles being unequally spaced longitudinally of said tubes to provide a first, a second and a third gas pass, the width of the first gas pass being much greater than that of 55 the second or third pass to compensate for the presence of said superheater elements in said first gas pass whereby the effective cross sectional area of each gas pass is substantially equal to that of the other gas passes to secure 60 substantially equal velocities for the flow of the gases in all of said passes.

In testimony whereof I have hereunto set my hand.

BENJAMIN N. BROIDO.
